UNITED STATES PATENT OFFICE.

HENRY W. BURR, OF CAMBRIDGEPORT, MASSACHUSETTS.

SHOE.

SPECIFICATION forming part of Letters Patent No. 248,287, dated October 18, 1881.

Application filed December 16, 1880. (No model.)

To all whom it may concern:

Be it known that I, HENRY W. BURR, a citizen of the United States, residing at Cambridgeport, in the county of Middlesex and

5 State of Massachusetts, have invented certain new and useful Improvements in Shoes; and I hereby declare the following to be a full, clear, and exact description of the invention, such as will enable others skilled in the art 10 to which it appertains to make and use the same, reference being had to the accompanying drawings, and to letters or figures of reference thereon, which form a part of this specification.

15 The object of this improvement is to provide a shoe that shall admit the foot from the rear by turning downward and outward the flexible heel-section of the upper, while the quarters are separable along the rear of said 20 section,lapping over the same, and provided at their extremities with a suitable fastening device.

25 My invention consists in a shoe having an independent flexible heel-section or tongue capable of turning down outwardly and quarters overlapping such tongue and fastened outside thereof at their rear ends, the lower parts of said heel-section and quarters being joined permanently together on each side at a point 30 in rear of the breast of the heel.

35 The drawings illustrate my invention as applied to an overshoe; but it is equally adapted to other styles of shoes.

Figure 1 is a side view with one of the quarters raised and the heel-section turned down; Fig. 2, a perspective view of the shoe complete, and Fig. 3 a rear view.

In the drawings, A is the heel-section of the upper, rising from the rear of the heel, and 40 preferably extending about as high as the remainder of the upper. It is made flexible enough to turn down, as shown, so as to admit the foot from the rear.

45 B B are the quarters, having fastening devices F F at their extremities and preferably cut in one with the vamps C C, which are shown as united in front by a central seam, D. E E are rivets or stays inserted through the parts A and B at their junction with the fox- 50 ing. It is a peculiarity of my shoe that this point of junction is so far back as to be located in rear of the breast of the heel H.

The fastenings for the rear ends of the quar-

ters may be of any suitable form, such as hooks, lacings, or buttons, and will be so located as 55 to unite the opposite quarters detachably along the heel.

The drawings represent a spring-clasp of appropriate construction serving to bring the quarters nearly into contact and to lap them 60 over the heel-section.

If made to lap one upon the other, the tongue A may be considerably reduced in dimensions.

The shape given to the rear ends of the quarters and to the upright tongue A may be 65 varied according to the style of shoe desired, and a variety of effects may thus be produced without departing from the spirit of my invention.

The advantages of my improved shoe are, 70 principally, readiness of putting on and off, absence of fastenings in front or sides, ease of movement to the foot, due to the yielding of the quarters at the rear, and, finally, that snow, sand, &c., are not forced beneath the 75 quarters by the forward movement of the foot in walking.

I am aware that in sandals and some other forms of shoes the foot enters from the rear, and also that straps passing around the foot, 80 above the heel, have been used to secure shoes in position; but I am not aware of a shoe, prior to my invention, having a flexible tongue extending up from the heel beneath overlapping quarters provided at their rear ends with 85 fastening devices and stayed on both sides to the lower part of the flexible tongue back of the breast of the heel, so as to give strength and yet permit free turning down and up of the tongue for ready insertion of the foot from 90 the rear and subsequent lapping of both quarters over the heel-section.

I therefore claim as of my invention—

A shoe having quarters separable at the heel and provided at their extremities with 95 fastening devices, in combination with a flexible heel-section, as described, to which the quarters are stayed at points in rear of the breast of the heel, substantially as set forth.

In testimony whereof I affix my signature in 100 presence of two witnesses.

HENRY W. BURR.
